ROTARY CUTTER

Benjamin H. Flynn, Alexandria, La.

Application October 25, 1934, Serial No. 749,982

8 Claims. (Cl. 37—108)

The invention relates to improvements in rotary cutters having projecting teeth, and refers particularly to cutters of this character designed primarily for hewing off rough and undulatory surfaces of roadways such as those formed from gravel, macadam and the like.

It is one object of the invention to provide an exceptionally simple and inexpensive, yet an efficient, durable and easily adjustable construction for holding the cutting teeth in place upon the drum or other rotary member by which they are carried.

Another object of the invention is to provide a cutting tooth of new and improved form which will effectively cleave both downwardly and rearwardly through the work and will well withstand the severe strains to which it is subjected.

Yet another object is to provide a cutting tooth which will be self-sharpening.

With the foregoing in view, the invention resides in the novel subject matter hereinafter described and claimed, description being accomplished by reference to the accompanying drawing.

Fig. 1 is a vertical transverse sectional view through a rotary cutter constructed in accordance with the invention.

Figs. 2 and 3 are detail vertical sectional views on lines 2—2 and 3—3 of Fig. 1, respectively.

Fig. 4 is a fragmentary elevation showing one of the tooth holders when viewed in the direction indicated by the arrow A of Fig. 1.

Fig. 5 is a perspective view of one of the removable tooth-clamping lugs.

Fig. 6 is a perspective view of one of the teeth.

Fig. 7 is a detail view similar to a portion of Fig. 1 showing the tooth released.

A preferred construction has been shown and will be rather specifically described with the understanding however, that within the scope of the invention as claimed, variations may be made.

The rotary member 1 which is shown in the form of a drum, rigidly carries holders 3 for the teeth 9, said drum being preferably provided with openings 10 at the inner ends of said holders, through which the teeth extend. As all of the holders are of identical construction, a description of one will suffice. In the present showing, a curved base plate 11 is provided to lie against the outer side of the drum 1, drum and base plate being secured together by bolts or the like 12. Integral with and projecting outwardly from the base plate 11 is a channel-shaped tooth-abutting and receiving lug 13, the channel 14 of said lug being open in the direction in which the cutter

rotates. At the inner end of this channel, the base plate 11 is formed with an opening 15, one wall 16 of which constitutes an abutment in spaced opposed relation with the closed side 14^a of the channel 14, said opening and channel being in communication with each other. At its inner end, the closed channel side 14^a is beveled as shown at 14^b, providing a fulcrum 14^c at the inner end of the bevel, for a purpose to appear. The depth of the channel 14 and the corresponding dimension of the opening 15, are considerably greater than the thickness of the tooth 9, as seen most clearly in Fig. 3, and the portions of said channel and opening which are not occupied by said tooth, receive a removable tooth-clamping lug 17. The inner end of this lug is snugly received in the opening 15 and is provided with a face 18 which contacts with the abutment 16. The outer end of the lug 17 is formed with lateral ears 19 disposed adjacent similar ears 20 on the channel-shaped tooth-receiving lug 13, and clamping bolts 21 pass through openings in the two sets of ears. As long as these bolts are kept tight, they hold one end of the lug 17 and the other end of said lug is held by the abutment 16 so that the tooth 9 is rigidly held but when said bolts are sufficiently loosened (see Fig. 7), the tooth 9 and the lug 17 may rock as a single unit about the fulcrum 14^c, thereby loosening the engagement of the lug surface 18 with the abutment 16 and entirely freeing the tooth to allow easy adjustment or removal thereof. When the bolts 21 are tightened, the tooth 9 and lug 17 rock as a single unit upon the fulcrum 14^c to the limit allowed by the lug surface 18 striking the abutment 16. When this occurs, the tooth 9 is not quite in contact with the wall 14^a toward the outer end of the latter and the final tightening of the bolts 21 therefore springs the tooth until it is drawn solidly against said wall 14^a. The tooth is thus not only positively clamped in place but is held under tension and it is therefore so effectively held as to prevent it from slipping out of adjustment.

Preferably each tooth 9 is about two inches wide and one-half inch thick and to insure that the blows shall be delivered in the most advantageous direction, said teeth are longitudinally curved. Each tooth is also of obtuse angular form in transverse section as shown and this formation so stiffens the tooth that it will well withstand all strains to which it is subjected. The transversely angular formation of the tooth also provides the front side of said tooth with a central longitudinal corner 22 for cleavage en-

gagement with the work. The part of this corner at the extreme outer end of the tooth always strikes the work first and it is thus more easy for the tooth to penetrate hard material. The transversely angular form of the tooth also causes it to have a tendency to laterally move the particles of gravel, rock and the like with which it comes in contact, so that loosening of the surface material of the roadway and effective hewing off may be easily accomplished.

When the tooth 9 is of the obtuse angular cross section above described, the springing of said tooth caused by final tightening of the bolts 21, tends to widen the obtuse angle and force the edges of the tooth solidly against the side walls 14^d of the channeled lug 13.

By preference, the front side of each tooth 9, for a suitable part of its length, is of a metal much harder than the remainder of the tooth, the hard metal being denoted at 23. This will insure not only longer life but a self-sharpening tooth. At the opposite side of the tooth a central hard metal portion 24 may also be provided. This will prevent excessive wear in the region of the cleavage corner 22 which always strikes the hard surface first.

A rotary cutter of or substantially of the construction herein disclosed, will effectively cleave both downwardly and rearwardly through the work as it rotates and it will be observed that the front-to-rear dimension of each cutting blade is so slight that said blade possesses practically no "heel" to either interfere with downward penetration of the work or to create excessive braking action retarding the rotation of the cutter. The blades or teeth 9 being longitudinally adjustable in the clamps of the shaft or drum 7, can be adjusted beyond said clamps as long as sufficient portions of said blades or teeth remain to be held by said clamps, so that extreme economy is effected in operation of the cutter.

When the various teeth 9 are of the shape herein disclosed, the holders 8 are of course correspondingly shaped. It will be understood however, that insofar as the tooth-holding means is concerned, it is not restricted to use with curved teeth, nor with transversely angular teeth, nor is it restricted to the exact details of construction which have been herein disclosed for illustrative purposes.

I claim:

1. In a means for securing a cutting tooth to a rotary member, a tooth-abutting lug and an abutment between which to insert the tooth, said abutment and lug being both rigidly carried by said rotary member and being spaced apart a distance greater than the thickness of the tooth, a removable tooth-clamping lug having an inner end portion inserted between said abutment and the tooth, the outer ends of both of said lugs being sufficiently wide to project laterally in opposite directions from the tooth, and clamping bolts passing through said projecting portions.

2. In a means for securing a cutting tooth to a rotary member, a rigid channel-shaped tooth-receiving lug projecting beyond the periphery of said rotary member and having its channel of a depth greater than the thickness of the tooth, a removable tooth-clamping lug received in said channel, and clamping bolts for securing the two lugs together and positioned to straddle the tooth.

3. In a means for securing a cutting tooth to a rotary member, a rigid channel-shaped tooth-receiving lug projecting beyond the periphery of

said rotary member and having a channel of a depth greater than the thickness of the tooth, a removable tooth-clamping lug received in said channel, said rotary member being provided with an abutment abutting the outer side of said removable lug at the inner end of the latter, and clamping bolts securing the outer ends of the two lugs together and positioned to straddle the tooth.

4. In a means for securing a cutting tooth to a rotary member, a base plate for attachment to the periphery of said member, said base plate having an integral outwardly projecting channel-shaped tooth-receiving lug and having an opening at the inner end of said lug, said opening communicating with the channel of said lug to receive the inner end of the tooth, the depth of said channel and the corresponding dimension of said opening being greater than the thickness of the tooth, a removable tooth-clamping lug received in said channel and having its inner end snugly received in said opening, and clamping bolts securing the outer ends of said lugs together and positioned to straddle the tooth.

5. In a means for securing a cutting tooth to a rotary member, fixed and movable lugs to lie against opposite sides of the tooth, said fixed lug being rigidly carried by and projecting from the rotary member, clamping bolts engaged with the two lugs and positioned to draw the outer end of the movable lug and the tooth toward the fixed lug, said fixed lug having a tooth-engaging fulcrum upon which the tooth and the movable lug rock as a single unit when said bolts are tightened, and an abutment in fixed relation with said fixed lug, said abutment being disposed near the inner end of said movable lug in position to abut the outer side of the latter, said abutment being adapted to limit said rocking of said movable lug and tooth as said tooth is drawn completely against said fixed lug, whereby both the outer and the inner ends of the lugs are caused to solidly grip the tooth.

6. A structure as specified in claim 5; said fixed lug having a channel to snugly receive a transversely V-shaped tooth; the parts being related to longitudinally spring said tooth as the bolts are finally tightened, thereby widening the angle of the V and forcing the edges of the tooth tightly against the sides of said channel.

7. A rotary cutter tooth curved longitudinally, said tooth being of obtuse angular form in transverse section throughout its length to stiffen it and to provide the tooth with a work-cleaving corner, the front portion of said tooth being formed of metal much harder than the remainder of the tooth to provide a self-sharpening construction, the back of said tooth being provided with a central hardened portion preventing excessive wear of the tooth in the region of said work-cleaving corner.

8. A rotary cutter comprising a rotatable shaft having spaced radially projecting rigidly attached tooth clamps, and longitudinally curved cutting teeth fixedly held by said clamps and longitudinally adjustable therein to permit projection of said teeth from said clamps until wear no longer permits such adjustment, each of said teeth being of uniform width from end to end, of uniform thickness from end to end, and of uniform obtuse angular form in transverse section from end to end, the inside of the tooth curvature and the outside of the obtuse angle being presented in the direction in which the cutter rotates.
